DRAFT RIGGING

John H. Link, Merion, Pa., assignor to W. H. Miner, Inc., Chicago, Ill., a corporation of Delaware

Application May 28, 1932. Serial No. 614,657

5 Claims. (Cl. 213—9)

This invention relates to improvements in draft riggings for mine cars.

One object of the invention is to provide shock absorbing means especially adapted for mine cars for absorbing the draft and buffering shocks, so designed that both the draft and buffering shocks are absorbed by the same shock absorbing means but only half of the capacity of the shock absorbing means is employed in draft. 10 Another object of the invention is to provide in a mechanism of the character specified in the preceding paragraph simple and efficient means for transmitting the draft forces from the draft member to the shock absorbing means in such a 15 manner that the movement of the draft member will be greater than the amount of compression of the shock absorbing means produced thereby so that the total movement of the draft member will equal the movement of the buffering member 20 of the rigging while the shock absorbing means is compressed only to half of its compression stroke.

Other objects of the invention will more clearly appear from the description and claims 25 hereinafter following.

In the drawing, forming a part of this specification, Figure 1 is a horizontal sectional view, partly broken away, through one end of a mine car, illustrating my improvements in connection 30 therewith. Figure 2 is an elevational view of the structure shown in Figure 1, looking upwardly in said last named figure. And Figures 3 and 4 are vertical sectional views, corresponding respectively to the lines 3—3 and 4—4 of Figure 2.

35 In said drawing, 10 designates the vertical end wall of a mine car, and 11 the floor of said car. As shown in Figure 2, the middle section of the floor of the car is depressed, the bottom of said depressed portion being formed by a longitudinally extending plate 12, and the side walls being defined by beams 13—13, which in effect form sill members extending lengthwise of the car. The beams 13—13 have top and bottom flanges 14 and 15, the top flange 14 of each beam being 40 fixed to the bottom of the car and the bottom flange 15 supporting the floor plate 12.

45 My improved draft rigging comprises a main supporting casting A, which is fixed to the end of the car; a buffering head B; a draft member C; a lever D; and a spring resistance comprising three coils E—E—E.

The casting A has a vertical wall 16, side flanges 17—17, and a bottom flange 18. The upper end of the wall 16 of the casting A overlaps the 50 end wall 10 of the car, as clearly shown in Figure

3, and is secured thereto by rivets or other similar securing elements. The two side flanges 17—17 are riveted to the vertical web sections of the longitudinally extending beams 13—13, and the bottom flange 18 is secured to the floor plate 60 12. On the outer side at the bottom thereof the casting A is provided with a fulcrum ledge 19 having a seat 20 thereon. The casting A also has two pairs of outwardly projecting guide arms 21—21 and 21—21, which serve to slidably support the buffering head B, as hereinafter pointed out.

The buffering head B has a vertical front wall 22, which is transversely curved so as to provide an outer buffering surface adapted to engage with 70 a similar buffering head on the adjacent car. The buffering head B is hollow and has spaced top and bottom walls 23 and 24, which are connected by vertical side walls 25—25. The midsections of the top and bottom walls of the buffering head B 75 are cut away at the rear side, as indicated at 26—26, so as to accommodate the lever D for swinging movement. As clearly illustrated in Figures 2 and 4, the guide arms 21—21 embrace 80 the top and bottom walls 23 and 24 of the buffering head, thereby slidably supporting the head for movement toward and away from the end of the car. Outward movement of the buffering head B is limited by a pair of vertically arranged bolts 85 27—27, which extend through aligned openings in the pairs of top and bottom arms 21—21 and the top and bottom walls 23 and 24 of the buffering head B. The openings in the top and bottom walls of the buffering head are in the form of slots 28—28 so as to permit the required inward movement of the buffering head during a buffering action. In addition to limiting the outward movement of the buffering head, the bolts 27—27 serve to connect the buffering head to the supporting casting A and hold the parts of the mechanism 90 95 assembled.

The lever D is in the form of a casting having a relatively wide lower end section 29 engaged in the seat 20 of the ledge 19 of the casting A. The bottom end of the section 29 is rounded, as indicated at 130, so as to provide the proper fulcruming action. At the upper end, the lever D is forked, the members of said forked portion, which are indicated by 30—30, being connected by a transverse barlike section 31 formed integral 100 therewith. The rear of the barlike section 31 is rounded off, as clearly shown in Figure 3.

The draft member C, which is in the form of a U-shaped yoke strap, is connected to the forked upper end portion of the lever D, the arms 32—32 110

of said yoke having aligned openings 33-33 at their outer ends adapted to receive a coupling pin 34, which is engaged through the usual coupling link 35. As is well understood, the coupling link 5 35 serves to connect the car to the adjacent car. In order to accommodate the lower end of the pin 34, the top wall 23 of the buffering head B is longitudinally slotted, as indicated at 36. The lever D is widened between the upper and lower ends, as 10 indicated at 37, said widened portion being provided with three forwardly facing spring pockets 38-38-38.

The shock absorbing spring means, which comprises the three coils E-E-E, opposes inward 15 movement of the buffering head B and outward movement of the pivoted lever D. The three springs E-E-E are disposed within the buffering head and have their front and rear ends bearing respectively on the front end wall of the 20 buffering head B and on the section 37 of the lever D. The rear ends of the three springs are seated respectively in the pockets 38-38-38 of said lever. As clearly illustrated in Figure 3, the 25 rear edges of the top and bottom walls 23 and 24 of the buffering head B are normally spaced from the forward side of the lever D so as to permit the necessary forward swinging movement of said lever in draft and also limit the movement of the lever when the draft stroke has been completed. 30 The lever D normally bears on the vertical wall 16 of the supporting casting A, said wall forming in effect stop means for the rearward movement of the lever D.

The operation of my improved draft rigging 35 is as follows: Upon a buffering force being applied to the buffering head B, the latter is forced inwardly toward the end of the car, thereby compressing the three springs E-E-E against the lever D, which at this time is held stationary by the stop 40 wall 16 of the casting A. The buffering stroke of the head B is limited by engagement of said head with the lever D.

Upon a pulling action being applied to the link 35 in draft, the pull is transmitted through the 45 yoke C to the upper end of the lever D and the latter is rocked on its fulcrum end portion 29, thereby compressing the three springs E-E-E from their rear ends. During this time, the buffering head B acts as abutment means for the 50 front ends of the springs E-E-E, the bolts 27-27 holding the buffering head B against outward movement. Forward movement of the lever D is limited by engagement with the buffering head B. When the movement of the lever D is limited 55 in draft, the springs E-E-E will have been compressed to an amount which is half of the compression thereof during a buffering stroke of the buffering head B. Inasmuch as the lever D is connected at its upper end to the yoke C and has its 60 lower end fulcrumed on the support A, the intermediate portion of the lever D, which engages the springs E-E-E, will be pulled outwardly substantially half the distance that the yoke is pulled outwardly by the link 35, thus permitting a total 65 travel of the yoke C which is equal to the movement of the buffering head during a complete buffering stroke while effecting compression of the springs E-E-E to an extent which is approximately half of the full compression stroke thereof.

I have herein shown and described what I now consider the preferred manner of carrying out my invention, but the same is merely illustrative and I contemplate all changes and modifications that come within the scope of the claims appended 80 hereto.

I claim:

1. In a draft rigging for mine cars, the combination with a buffering head at the end of the car supported for movement inwardly toward said end of the car; of a shock absorbing device opposing inward movement of said head; a draft member movable away from the car; and a lever fulcrumed at one end on the car and connected at the other end to said draft member, said lever having the midsection thereof engaging with said shock absorbing device to compress the same. 85

2. In a draft rigging for mine cars, the combination with a supporting structure fixed to the end of the car; of a buffering head slidingly carried by said supporting structure; a shock absorbing means opposing inward movement of the buffering head; a draft member adapted to be coupled to an adjacent car; and a lever fulcrumed at one end on said supporting structure 95 and having the other end swiveled to said draft member, the midsection of said lever engaging the rear end of said shock absorbing means to transmit draft shocks thereto. 100

3. In a draft rigging for mine cars, the combination with a supporting structure fixed to the end of the car; of a buffering head slidingly carried by said supporting structure; a shock absorbing means opposing inward movement of the buffering head; a draft member adapted to 105 be coupled to an adjacent car; and a lever fulcrumed at its lower end on said supporting structure and having its upper end connected to the inner end of the draft member, said lever bearing between its ends on the inner ends of 110 said shock absorbing means.

4. In a draft rigging for mine cars, the combination with a supporting structure fixed to the end of the car, said structure having a ledge at the bottom thereof; of a lever fulcrumed at 115 its lower end on said ledge; shock absorbing means bearing at its inner end on said lever at a point above the fulcrum thereof; a draft member swiveled to the upper end of said lever; and a buffering head engaging the outer end of said 120 shock absorbing means, said buffering head being slidingly carried on the supporting structure. 125

5. In a draft rigging for mine cars, the combination with a supporting structure fixed to one end of the car, said supporting structure having 130 a stop face and a ledge, said ledge being at the bottom of the stop face; of a lever fulcrumed at its lower end on said ledge and held against rearward rocking movement by said stop face; a spring having the rear end thereof bearing 135 on the forward side of said lever at a point between the ends of said lever; means swiveled to the upper end of the lever for connecting the same to the coupling means of an adjacent car; and a buffering head slidingly guided on said supporting structure, said buffering head bearing on the outer end of said spring. 140

JOHN H. LINK.
